UNITED STATES PATENT OFFICE.

CHARLES ZIMMERLING, OF PHILADELPHIA, PENNSYLVANIA.

IRONING-TABLET.

SPECIFICATION forming part of Letters Patent No. 373,168, dated November 15, 1887.

Application filed October 25, 1886. Serial No. 217,111. (No model.)

To all whom it may concern:

Be it known that I, CHARLES ZIMMERLING, a citizen of the United States, residing in the city and county of Philadelphia, State of Pennsylvania, have invented a new and useful Improvement in Ironing-Tablets, which improvement is fully set forth in the following specification and accompanying drawings, in which—

Figure 1 represents a perspective view of an ironing-tablet embodying my invention. Fig. 2 represents a section thereof in line xx , Fig. 1. Fig. 3 represents a bottom plan thereof.

Similar letters of reference indicate corresponding parts in the several figures.

15 My invention consists of an ironing-tablet in which the face is available for the application of a hot iron and the back adapted to admit portions of the same to be scraped or shaved off for mixing with the starch.

20 Referring to the drawings, A represents a piece or cake of beeswax, paraffine-wax, or other analogous material suitable for ironing purposes.

B represents a slotted plate, preferably of 25 metal, which is laid on the face of the cake and provided with points, prongs, or spurs C, which are forced into the same, whereby the plate is held in position and prevented from lateral displacement.

30 D represents a strip or band of paper or other material which is passed around the cake A and has its ends pasted or gummed together, whereby the plate B is prevented from outward displacement.

35 E represents a label or piece of paper which occupies the back of the cake and contains directions for use of the tablet, said label being pasted or gummed to the band D.

The spurs C are integral with the plate B 40 and turned down from the same, so as to penetrate the wax.

The operation is as follows: The label and band are removed, whereby the plate or top B of the tablet is uncovered and the back of the wax exposed. The hot iron is placed upon 45 the plate and heats the same, thus melting the contiguous wax, the melted wax rising through the openings in the plate and reaching the bottom of the iron, thus waxing the same for purposes of ironing. When the ironing is finished, the plate is embedded in the cold wax and so retains its position, there remaining on the plate a thin film of wax, which is melted by the next application of the iron, and thus the tablet may be used until exhausted. 50

I am aware that it is not new to construct an ironing-tablet having a perforated plate in connection with a piece of wax, and I do not claim the same; but in such device the perforated plate has a border or rim which embraces 55 the sides of the stand, thereby covering the sides of the piece of wax, so that some of the melted wax which passes through the perforations flows down the sides of the rim, needing to be removed therefrom. This is avoided by 60 securing the plate to the wax by means of the spurs and dispensing with the rim, the overflowing wax coming in contact and uniting with the main body or piece of wax. 65

Having thus described my invention, what I 70 claim as new, and desire to secure by Letters Patent, is—

As an improved article of manufacture, an ironing-tablet consisting of a piece of wax and a perforated plate with spurs, the plate being 75 secured to the piece of wax by means of the said spurs, all substantially as and for the purpose set forth.

CHARLES ZIMMERLING.
